US0D1077049S

(12) **United States Design Patent** (10) Patent No.: **US D1,077,049 S**
(45) Date of Patent: ** May 27, 2025

(54) **ELECTRONIC SHELF LABEL**

(71) Applicant: **Hanshow Technology Co., Ltd.**,
Jiaxing (CN)

(72) Inventors: **Zongdi Zheng**, Zhejiang (CN); **Shiguo Hou**, Zhejiang (CN); **Jianguo Zhao**, Zhejiang (CN); **Ming Shen**, Zhejiang (CN); **Xubing Du**, Zhejiang (CN); **Linjiang Wang**, Zhejiang (CN); **Zhong Wang**, Zhejiang (CN); **Wei Wang**, Zhejiang (CN)

(**) Term: **15 Years**

(21) Appl. No.: **35/521,265**

(22) Filed: **Apr. 30, 2024**

(80) **Hague Agreement Data**

Int. Filing Date: **Apr. 30, 2024**

Int. Reg. No.: **DM/237464**

Int. Reg. Date: **Apr. 30, 2024**

Int. Reg. Pub. Date: **Jun. 14, 2024**

(30) **Foreign Application Priority Data**

Nov. 10, 2023 (CN) 202330736537

(51) LOC (15) Cl. **20-03**

(52) U.S. Cl.

Primary Examiner — Catherine Ho

(57) **CLAIM**

The ornamental design for an electronic shelf label as shown and described.

DESCRIPTION

1. Electronic shelf label

1.1 : Front

1.2 : Back

1.3 : Left

1.4 : Right

1.5 : Top

1.6 : Bottom

1.7 : Perspective

1.8 : Perspective

(Continued)

The intended use of the electronic shelf label is for an electronic device for displaying information such as product name and price.

1 Claim, 8 Drawing Sheets
